UNITED STATES PATENT OFFICE

1,993,711

STEAM GENERATOR

George W. Bach, Erie, Pa., assignor to Union Iron Works, Erie, Pa., a corporation of Pennsylvania

Application May 2, 1932, Serial No. 608,717

3 Claims. (Cl. 122—478)

Steam generators are preferably supplied with superheaters. The present invention is designed to improve and simplify the arrangement of superheaters in connection with steam boilers. Features and details of the invention will appear from the specification and claims.

Preferred embodiments of the invention are illustrated in the accompanying drawing as follows:—

10 Fig. 1 shows a central vertical section through a boiler on the line 1—1 in Fig. 2.

Fig. 2 a section on the line 2—2 in Fig. 1, a part of the drum being broken away to better show the construction.

15 1 marks the furnace in which the boiler is mounted, 2 a front drum, 3 a rear drum, 4 a bottom drum, 5 and 6 steaming banks of tubes between the lower and front drum, 7 down-take tubes between the rear drum and lower drum, 8 upper water tubes connecting the drums, and 9 upper steam tubes connecting the drums. A baffle 10 is provided carrying the gases from the furnace to a pass upwardly and downwardly between the upper drums.

25 The steam tubes 9 discharge into a channel 11 arranged within the rear drum. This channel has open ends 12 communicating with the rear drum. Superheater tubes 13 lead from the channel 11 across the upper part of the furnace toward the front drum and has a return loop 14 leading to the rear drum. A chamber 15 receives the steam from the return loop 14 and a steam discharge pipe 16 leads from the chamber. The chamber 15 has closed ends 17 so that there 30 is no mixture between the superheated steam and the saturated steam.

In order that the generator may be self-draining the chamber 15 has a slight drainage opening 18 permitting the drainage of water from the chamber 15 to the rear drum. This opening, however, is not sufficient to involve any material movement of steam from the rear drum to the chamber. In this it will be seen that a 40 very simple and convenient structure is provided. The channel and chamber walls may be formed of very light metal as the pressures are practically balanced within the rear drum.

What I claim as new is:—

50 1. In a steam generator, the combination of

a front drum; a rear drum; a downwardly extending circulating system connecting said drums and comprising steaming and down-take tubes, the major portion of the steaming tubes leading to the front drum; upper water tubes connecting the front and rear drums; upper steam tubes connecting the front and rear drums; a connecting channel at the rear drum into which the steam tubes discharge; superheater tubes leading from the channel and extending toward the front drum and returning to the rear drum; a chamber in the rear drum to which the superheater tubes discharge; and a steam discharge from the chamber.

2. In a steam generator, the combination of 15 a front drum; a rear drum; a downwardly extending circulating system connecting said drums and comprising steaming and down-take tubes, the major portion of the steaming tubes leading to the front drum; upper water tubes 20 connecting the front and rear drums; upper steam tubes connecting the front and rear drums; a connecting channel at the rear drum into which the steam tubes discharge, said channel opening to the rear drum; superheater tubes leading from the channel and extending toward the front drum and returning to the rear drum; a chamber in the rear drum to which the superheater tubes discharge; and a steam discharge 25 from the chamber.

3. In a steam generator, the combination of 30 a front drum; a rear drum; a downwardly extending circulating system connecting said drums and comprising steaming and down-take tubes, the major portion of the steaming tubes leading to the front drum; upper water tubes connecting the front and rear drums; upper steam tubes connecting the front and rear drums; a connecting channel at the rear drum 35 into which the steam tubes discharge; superheater tubes leading from the channel and extending toward the front drum and returning to the rear drum; a chamber in the rear drum to which the superheater tubes discharge; and a steam discharge 40 from the chamber, said channel extending through the chamber and connecting with the rear drum.
